Assistant Examiner — Clesse Moore, Jr.

(74) Attorney, Agent, or Firm — Loza & Loza, LLP;
Derek Yeung(57) **CLAIM**

I claim the ornamental design for a vehicle floor mat, substantially as shown and described.

DESCRIPTION

FIG. 1 is a perspective view of a vehicle floor mat.

FIG. 2 is a top plan view of the vehicle floor mat of FIG. 1.

FIG. 3 is a bottom plan view of the vehicle floor mat of FIG. 1.

FIG. 4 is a front elevational view of the vehicle floor mat of FIG. 1.

The rear elevational view of the vehicle floor mat of FIG. 1 is substantially the same as FIG. 4; and,

FIG. 5 is a right side elevational view of the vehicle floor mat of FIG. 1.

The left side elevational view of the vehicle floor mat of FIG. 1 is substantially the same as FIG. 5.

The broken lines shown illustrate portions of the vehicle floor mat that form no part of the claimed design.
